BOOKHOLDER

Frank Seidel, Detroit, Mich.

Application November 8, 1946, Serial No. 708,509

10 Claims. (Cl. 45—85)

1

The present invention pertains to a novel holder for books, such as telephone directories, for example.

The principal object of the invention is to provide a collapsible holder that may be attached to a wall to hold the book in closed or open position, as desired. In the case of telephone directories, for example, it is often desirable to have the same within easy access from a desk and not in a horizontal position where it occupies a substantial area even when closed. Accordingly, the invention provides a holder that supports the book in closed position against a vertical wall. The holder embodies a pair of lazy-tongs by means of which it is extensible to bring the book to a horizontal position when it is to be opened.

More particularly, the device comprises a suitable back plate adapted for attachment to a wall and having two sets of lazy-tongs attached thereto and extensible therefrom. A pair of book supporting plates are pivotally attached respectively near the stationary and movable ends of the lazy-tongs and are joined by an intermediate hinge structure. Thus, when the lazy-tongs are expanded, the plates come to a nearly horizontal position with the book supported thereon. When the lazy-tongs are compressed, the hinge between the plates drops to a nearly vertical position, holding the closed book between them, with both the book and the supporting structure in a compact condition against the wall.

The hinge connection between the book supporting plates is expandable to accommodate various thicknesses of books. Certain of the pivotal points of the lazy-tongs are joined by articulated linkage that prevents collapsing of the tongs. This linkage is also adjustable to conform with the adjustment of the hinge structure.

The invention is fully disclosed by way of example in the following description and in the accompanying drawings in which:

Figure 1 is a side view of the device in closed position;

Figure 2 is a front elevation on the line 2—2 of Figure 1;

Figure 3 is a side view of the device in expanded or open position;

Figure 4 is a section on the line 4—4 of Figure 3;

2

Figure 5 is a detail plan view, partly broken away, on the line 5—5 of Figure 3;

Figure 6 is a section on the line 6—6 of Figure 3, and

Figure 7 is a section on the line 7—7 of Figure 5.

Reference to these views will now be made by use of like characters which are employed to designate corresponding parts throughout.

10 In Figures 1 and 3 is shown a back plate 1 adapted to be secured to a vertical wall A by suitable fastenings 2. The area of the plate against the wall is somewhat in excess of the cover area of the book to be supported. The lower portions of the vertical edges of the plate 1 are flanged at 3 away from the wall and slotted vertically at 4 for a purpose that will presently be described. The upper horizontal edge is also flanged horizontally as indicated by the numeral 5 in Figures 1 and 3. Beneath the flange 5, near each end thereof, is welded a clip 6 extending perpendicular to the plate 1 and formed with lugs 7 and 8 at its respective ends.

25 A book cover plate 9 is supported from the lugs 8 by means of hinge members 10 fastened to one edge of the plate and pivotally attached to the lugs by suitable pins 11. Hinges 12 are attached to the edge of the plate 9 parallel to and more remote from the back plate 1 and carry a relatively narrow book end or binding plate 13 as shown more clearly in Figure 7. The member 13 is slotted transversely at 14 and beneath it is mounted a complementary but wider book end or binding plate 15 formed with transverse slots 16

30 registering with the slot 14. The plates 13 and 15 are fastened together by bolts 17 passed through the aligned slots and tightened by nuts 18. Another cover plate 19 is attached to the member 15 by means of hinges 20, the plate 13 being notched at 21 to accommodate these hinges. The binding of the book lies against the plate 13, and it is evident that the plate 15 may be adjusted laterally and relatively to the plate 13 to accommodate various thicknesses of books.

35 Lazy-tongs comprising crossed levers 22, 23 are mounted at the lateral edges of the plates 9, 19 and supported at one end from the back plate 1. At one end of each set of lazy-tongs, the upper end of the lever 22 is pivotally attached to the corresponding lug 7 by a pin or rivet 24. The

free or lower end of the adjacent lever 23 is mounted in the slot 4 of the corresponding flange 3 by a rivet 25. The lugs 8 lie inward of the lugs 7, as shown in Figure 4, to bring the plates 9, 19 between the lazy-tongs.

Links 26 are connected to opposed upper pivotal points of the respective lazy-tongs and extend toward the free ends of the tongs, as shown in Figures 3 and 5. The links are held by elongated rivets 27 at the said pivotal points and are spaced outwardly from the tongs by collars 28. These links are overlapped by similar links 29 attached respectively to the upper ends of the outermost levers 23. The lower edges of the links 26 are recessed at 30 to receive stops 31 on the lower ends of the links 29, whereby to prevent upward coupling. The overlapped links are pivotally attached to each other by a shoulder screw 32 receivable selectively in a series of apertures 33 formed through the overlapped parts of the links. The apertures 33 are above the center line of the upper pivotal connections of the lazy-tongs links, and by reason of the attachment 32, the collapse of the lazy-tongs under the weight of the book is prevented. The combined length of the links 26, 29 is adjusted at the apertures 33 and held in such adjustment by the pin 32, to compensate for the lateral adjustment of the plates 13, 15 for various thicknesses of books. The links 29 are preferably comprised in a continuous U-shaped strap having a back 29' as shown in Figure 2. A handle 34 is fastened centrally to the back 29' for expanding and contracting the device.

Angular clips or lugs 35 are fastened near the free or forward edge of the plate 19 for suspending the plate from rivets 36 on the upper ends of the foremost levers 23.

A book B is shown supported in open condition on the plates 9 and 19 in Figure 3. The binding of the books, as already stated, lies at the plates 13, 15. When the book is to be closed, the device is collapsed to the position shown in Figure 1 by pushing inward and upward on the handle 34. The links 26, 29 buckle downward, and their pivotal connections 32 also drop. The dropping of the lower pivotal connections of the levers 22, 23 is permitted by the sliding of the rivets 25 in the slots 4. The device is brought to open position by pulling outwardly on the handle 34, as a result of which the plates 9, 19 take a nearly horizontal position and the book can be opened thereon to the desired page. The compactness of the device when not in use is illustrated in Figure 1 wherein the entire space occupied thereby is only slightly larger than the volume of the closed book.

Although a specific embodiment of the invention has been illustrated and described, it will be understood that various alterations in the details of construction may be made without departing from the scope of the invention as indicated by the appended claims.

What I claim is:

1. A book holder comprising a back member adapted for attachment to a wall, two sets of lazy-tongs having one end connected thereto and extensible therefrom, a pair of plates supported between and respectively at the upper ends of said lazy-tongs, said plates being hinged to each other between said ends.

2. A book holder comprising a back member adapted for attachment to a wall, two sets of lazy-tongs having one end connected thereto and extensible therefrom, a pair of plates supported between and respectively at the upper ends of

said lazy-tongs, and an extensible hinge joining said plates between said ends.

3. A book holder comprising a back member adapted for attachment to a wall, two sets of lazy-tongs having one end connected thereto and extensible therefrom, a pair of plates supported between and respectively at the upper ends of said lazy-tongs, said plates being hinged to each other between said ends, and linkage joining two of the pivotal points of said lazy-tongs, whereby to limit the expansion of said lazy-tongs.

4. A book holder comprising a back member adapted for attachment to a wall, two sets of lazy-tongs having one end connected thereto and extensible therefrom, a pair of plates supported between and respectively at the upper ends of said lazy-tongs, and an extensible hinge joining said plates between said ends, and linearly adjustable linkage joining two of the pivotal points of said lazy-tongs, whereby to limit the expansion of said lazy-tongs.

5. A book holder comprising a back member adapted for attachment to a wall, two sets of lazy-tongs having an upper end pivotally attached to said member and extensible therefrom, slotted flanges on said member below said ends, a lower end of each of said lazy-tongs being slidably mounted in each of said flanges, a pair of plates supported between and respectively at the upper ends of said lazy-tongs, said plates being hinged to each other between said ends.

6. A book holder comprising a back member adapted for attachment to a wall, two sets of lazy-tongs having an upper end pivotally attached to said member and extensible therefrom, slotted flanges on said member below said ends, a lower end of each of said lazy-tongs being slidably mounted in each of said flanges, a pair of plates supported between and respectively at the upper ends of said lazy-tongs, and an extensible hinge joining said plates between said ends.

7. A book holder comprising a back member adapted for attachment to a wall, two sets of lazy-tongs having an upper end pivotally attached to said member and extensible therefrom, slotted flanges on said member below said ends, a lower end of each of said lazy-tongs being slidably mounted in each of said flanges, a pair of plates supported between and respectively at the upper ends of said lazy-tongs, and an extensible hinge joining said plates between said ends, and linearly adjustable linkage joining two of the pivotal points of said lazy-tongs, whereby to prevent the collapse of said lazy-tongs.

8. A book holder comprising a back member adapted for attachment to a wall, two sets of lazy-tongs having one end connected thereto and extensible therefrom, a pair of plates supported between and respectively at the upper ends of said lazy-tongs, said plates being hinged to each other between said ends, and articulated linkage joining two of the pivotal points of said lazy-tongs, whereby to prevent the collapse of said lazy-tongs.

9. A book holder comprising a back member adapted for attachment to a wall, two sets of lazy-tongs having one end connected thereto and extensible therefrom, a pair of plates supported between and respectively at the upper ends of said lazy-tongs, and an extensible hinge joining said plates between said ends, and linearly adjustable articulated linkage joining two of the pivotal points of said lazy-tongs, whereby to prevent the collapse of said lazy-tongs.

10. A book holder comprising a back member

adapted for attachment to a wall, two sets of lazy-tongs having an upper end pivotally attached to said member and extensible therefrom, slotted flanges on said member below said ends, a lower end of each of said lazy-tongs being slidably mounted in each of said flanges, a pair of plates supported between and respectively at the upper ends of said lazy-tongs, and an extensible hinge joining said plates between said ends, and linearly adjustable articulated linkage joining two 10 of the pivotal points of said lazy-tongs, whereby to prevent the collapse of said lazy-tongs.
